PONY CART

Oscar A. Dammeier, New Bremen, Ohio

Application May 26, 1947, Serial No. 139,288

Term of patent 3½ years

(Cl. D14—3)

To all whom it may concern:

Be it known that I, Oscar A. Dammeier, a citizen of the United States, residing at New Bremen, in the county of Auglaize and State of Ohio, have invented a new, original, and ornamental Design for a Pony Cart, of which the following is a specification, reference being had to the accompanying drawing, forming a part thereof, wherein:

Figure 1 is a top plan view of a pony cart incorporating the new design; and

Figure 2 is a side elevational view of the pony cart, the upper portion of the sign standard being broken away for convenience of illustration.

The horizontal dot-dash lines extending to the left in Figures 1 and 2 diagrammatically

represent the pulling shafts of the cart and are for illustrative purposes only.

I claim:

The ornamental design for a pony cart, substantially as shown.

OSCAR A. DAMMEIER.
